M. L. Rison, Inventor

UNITED STATES PATENT OFFICE.

MASTIN LEE RISON, OF PARIS, TENNESSEE, ASSIGNOR TO THE PARIS SPRING MANUFACTURING COMPANY, OF SAME PLACE.

SPRING CHAIR-SEAT.

SPECIFICATION forming part of Letters Patent No. 637,667, dated November 21, 1899.

Application filed May 20, 1899. Serial No. 717,583. (No model.)

To all whom it may concern:

Be it known that I, MASTIN LEE RISON, a citizen of the United States, residing at Paris, in the county of Henry and State of Tennessee, have invented a new and useful Spring Chair-Seat, of which the following is a specification.

My invention relates to furniture-springs, and particularly to a spring-section adapted for use as a chair-seat, chair-back, portion of a bed-bottom or mattress, or in any other relation in which a group of coöperative spring elements is required; and the object in view is to provide such a combination of and relation between the spring elements as to accomplish the distribution of weight applied to any portion of the section, and thus enable the parts of the section to retain their shape after continued use.

My invention consists, essentially, of a spring-section comprising an outer frame or support, within which is arranged a series of spring elements radiating from a center plate or element, said springs being of conicohelical construction, and preferably have a body portion which is substantially conicosubulate, while the outer ends thereof are substantially conicohemispherical; and, furthermore, my invention consists in combining with each section a yielding reinforcing device by which pressure may be applied to the center of the section to oppose repression of the latter by a weight to which it may be subjected in use.

Further objects and advantages of this invention will appear in the following description, and the novel features thereof will be particularly pointed out in the appended claims.

In the drawings, Figure 1 shows the spring-section embodying my invention applied in the operative position to a chair to form a chair-bottom and back-spring. Fig. 2 is a sectional view of the spring-section. Fig. 3 is an inverted plain view of the same.

Similar reference characters indicate corresponding parts in all the figures of the drawings.

In the preferred embodiment of my invention as illustrated in the drawings the device consists of a frame 1, which may vary in contour and material to suit the article of furniture in connection with which the spring-

section is employed, a central button or connecting-plate 2, and a series of radiating spring elements 3, connecting said button or plate with the frame, the body portions of said spring elements being conicosubulate to adapt them to lie in close proximity, particularly when the section is designed for use as a chair-bottom, and having their outer ends reduced to form substantially conicohemispherical portions, whereby the outer extremities of the wires forming the spring elements may be engaged with the frame in such a way as to be concealed, and thus held wholly out of contact with the garments of a person occupying the article of furniture to which the device is applied. By this construction it will be seen that the spring elements have enlarged portions 9 near their outer ends, and these convexly-rounded outer portions 9 cause the section to bulge sharply adjacent to the frame, and thus insure that form and relation between the parts which is desirable, particularly in connection with the seat or back of a chair. In the construction illustrated the attachment of the outer extremities of the spring ends to the frame is accomplished by means of a metallic strip 4, secured to the frame, extending inward slightly beyond the inner surface thereof and provided with perforations with which the outer hooked or bent extremities of the springs engage; also, in the construction illustrated the central button or plate consists of a metallic disk suitably perforated for engagement with the adjacent inner extremities of the spring elements; but it will be understood that this feature is susceptible of variation to suit the designed use of the section.

In connection with the elements above described when the section is designed for use as a chair-bottom I preferably employ a reinforcing device consisting of a bearing-plate 5, connected with the frame by radial arms 6, and a spiral spring 7, bearing at its upper end against said plate and having its lowermost coil in turn connected with radial tension rods or wires 8, which hold the reinforcing-spring under the desired tension, and thus cause the latter to force the bearing-plate upward against the center of the group of elements forming the spring-section. The ra-

dial arms 6 serve to maintain the bearing-plate in its proper position in alinement with the center of the spring-section when depressed, and thus perform the function of ties 5 for preventing displacement when the device is in use.

Among the advantages of a spring-section constructed as described may be mentioned 10 lightness, strength, and durability, and it is obvious, furthermore, that it is of a suitably-ventilated construction, and while a covering may be used in connection therewith it is obvious 15 that the relative arrangement of the parts is such as to adapt the section for exposure, inasmuch as the extremities of the spring elements are concealed to avoid injury to the garments of the occupant of the article of furniture. Preferably the bearing-plate underlaps the adjacent inner coils of 20 the spring elements, whereby the upward pressure thereof serves to add to the bulging effect of the structure.

Various changes in the form, proportion, size, and minor details of construction within 25 the scope of the appended claims may be resorted to without departing from the spirit or sacrificing any of the advantages of the invention.

Having described my invention, what I 30 claim is—

1. A spring-section for furniture, comprising a frame, and a series of conicohelical spring elements radiating from a common center and attached at their outer extremities to the frame, said spring-sections having 35 enlarged portions near their outer ends, substantially as specified.

2. A spring-section for furniture, comprising a frame, and a series of conicohelical 40 spring elements radiating from a common center and attached at their outer ends to said frames, the body portions of said spring elements being conicosubulate and having their outer ends reduced, substantially as 45 specified.

3. A spring-section for furniture, comprising a frame, and a series of conicohelical spring elements radiating from a common center and attached at their outer ends to 50 said frame, the body portions of said spring elements being conicosubulate, and the outer reduced ends thereof approximately conico- 55 hemispherical, substantially as specified.

4. A spring-section for furniture having a frame, and a series of conicohelical spring 60 elements radiating from a common center and provided with convexly-rounded outer enlarged portions having reduced ends terminally attached to the frame, substantially as specified.

5. A spring-section for furniture comprising a frame, and a series of conicohelical spring elements radiating from a common center and attached at their outer ends to 65 said frames, the body portions of said spring elements being conicosubulate, and the outer ends approximately conicohemispherical, whereby convexly-enlarged portions are formed near their outer ends, substantially as specified.

6. A spring-section for furniture, comprising a frame provided with a perforated strip, a series of conicohelical spring elements radiating from a common center and attached at their outer ends with said perforated strips, 70 the body portions of said spring elements having enlarged portions near their outer ends, and a central button connecting the inner extremities of the spring elements, in combination with a spring reinforcing device 75 bearing upon said section in a direction perpendicular to the plane thereof and adjacent to its center, substantially as specified.

7. A spring-section for furniture, comprising a frame, a series of conicohelical spring 80 elements radiating from a common center and attached at their outer ends to said frame, and a central button connecting the inner extremities of the spring elements, in combination with a spring reinforcing device 85 comprising a bearing-plate arranged in contact with the spring-section at its center, arms or tie-rods radially connecting said bearing-plate with the frame, a spring arranged at its inner end in contact with said bearing-plate, and tension-rods radiating from the 90 outer coil of the spring and connected with the frame, substantially as specified.

In testimony that I claim the foregoing as my own I have hereto affixed my signature in 95 the presence of two witnesses.

MASTIN LEE RISON.
